UNITED STATES PATENT OFFICE.

HARTLEY BLYTH PRATT, OF BARROW-IN-FURNESS, ENGLAND, ASSIGNOR TO VICKERS LIMITED, OF WESTMINSTER, ENGLAND, A BRITISH COMPANY.

SUBMARINE MINE.

Application filed June 28, 1926, Serial No. 119,046, and in Great Britain November 27, 1925.

This invention relates to submarine mines of the kind provided with one or more safety devices controlled by the tension of the mooring cable. In such mines the safety devices have been actuated by a sliding rod which passes into the flotation chamber or mine proper and is connected directly or indirectly to the mooring cable and the consequent movement of the said rod has necessitated the provision of a water tight diaphragm of considerable flexibility in order to accommodate the comparatively large movements of the sliding rod. The chief object of the present invention is to provide an improved arrangement for actuating the safety device or devices in which the diaphragm is not subjected to the aforesaid large movements and can therefore be made of sufficient rigidity and strength to withstand the high hydrostatic pressures obtaining when the mine during the anchoring operation descends to a very considerable depth beneath the surface of the water.

According to the present invention the aforesaid sliding rod is replaced by a rocking lever provided at its rocking point with the aforesaid diaphragm which, therefore, partakes only of the rocking movements of the said lever. This lever is suitably connected to the mooring cable and also to the safety device or devices which, in the case of a mine that is fired electrically when one or other of a number of horns on the exterior of the mine is struck by a passing vessel, comprise a safety switch arranged in the circuit of the battery, which circuit includes the detonator, and a trigger or releasing device that normally holds the primer of the mine at a safe distance from the detonator and when moved into the disengaging position allows the primer to drop into the operative position in relation to the detonator.

The aforesaid rocking lever may be held in the inoperative position by a delay action device which prevents the said lever from being moved to close the switch and move the trigger to the releasing position until after the lapse of a predetermined interval of time from the moment of separation of the flotation chamber from the anchor. This device preferably comprises a soluble plug disposed in a chamber having an opening which is normally sealed by a plate of suitable material connected by a lanyard to

the anchor so that this plate is stripped and thus exposes the opening to the sea water when the flotation chamber separates from the anchor.

In order that the said invention may be clearly understood and readily carried into effect, the same will now be described more fully with reference to the accompanying drawings, in which:—

Figure 1 is a vertical section of the lower part of a flotation chamber or mine proper shewing a constructional form of the invention as applied to an electric mine,

Figure 2 is an underneath plan of Figure 1, with part in section,

Figure 3 is a section on a larger scale shewing the safety switch and its associated parts,

Figure 4 is a view of part of Figure 1 also on a larger scale, and

Figure 5 is a section shewing the time releasing device for the rocking lever that operates the safety devices.

A is the shell of the flotation chamber, A¹ is the upper end of the mooring cable, B is the aforesaid rocking lever, C is the detonator, C¹ is the safety switch, D is the primer and D¹ is the trigger which normally holds the primer in the raised position as is, per se, well understood.

In the example shewn the rocking lever B is provided with a ball pivot between the two halves B¹, B² of which the diaphragm B³ is clamped, the outer part of this diaphragm being clamped between the two halves A¹, A² of a spherical socket carried by the shell of the flotation chamber. The inner part of the said lever B which is disposed within the flotation chamber is connected by a link b to an arm c on a spindle c¹ carrying the safety switch C¹. This switch, as shewn in Figure 3, is of the double pole type and when in the closed position bridges the two fixed contacts C², C³ so as to complete the battery circuit as is well understood per se, this action occurring when the lever B is rocked in a clockwise direction in the manner hereinafter described. Further movement of the said lever in the same direction brings the edge of the inner arm of this lever against a toe d on the trigger D¹ (which is pivoted at d¹) and thereby moves this trigger away from the lower end of the primer D to allow the latter to fall into the operative position with respect to the deto-

nator C. The trigger D¹ is normally held in the operative position by a spring plunger D².

The outer arm of the rocking lever B is formed as a pivot to receive one end of an arm B⁴ the other end of which has a slot b⁴ to receive a detachable pin b⁵ on a spring plunger B⁵. The purpose of this pivotal connection is to enable the arm B⁴ to be 10 swung into the position shown by chain lines in Figure 2 to enable the detonator carrier to be inserted and removed. This carrier is retained in place by a pivoted lever B⁴ (Figures 1 and 2) in the known manner. 15 To the middle portion of the arm B⁴ is connected the mooring cable A¹. The said arm is normally held in the inoperative position shewn in Figure 1 by a lever E one arm of which bears against the lower part of the 20 spring plunger B⁵ and the other arm presses against a plunger E¹ held in its outermost position by a soluble plug E² disposed in a casing E³. Sea water is prevented from having access to the soluble plug until the 25 flotation chamber has separated from the anchor, by a metal plate e (Figure 2) which closes an opening e¹ in the casing E³. This metal plate is connected by a lanyard e² to the anchor and is stripped off by the pull 30 on this lanyard when the flotation chamber separates from the anchor. The lever E is positively held in the position shewn in Figure 3 by a shearing pin e³ which is sheared by the pull on the arm B⁴ after the 35 soluble plug E² has become dissolved which occurs after a predetermined interval of time.

The parts of the mine for obtaining the release of the flotation chamber from the 40 anchor and the anchoring of the flotation chamber at the set depth are preferably constructed in accordance with the specifications of two patent applications filed concurrently herewith. When the flotation chamber separates from the anchor the metal plate e is stripped off as explained above and sea water therefore has access to the 45 soluble plug E². The flotation chamber is anchored at the set depth before this plug has dissolved and when this occurs the pull 50 on the mooring cable due to the buoyancy of the flotation chamber causes the shearing pin e³ to be severed. The arm B⁴ then moves down against the resistance of the spring 55 of the plunger D² and the lever B is rocked in the manner above described to first move the switch C¹ to the closed position and to then move the trigger D¹ to the disengaging 60 position. The slot b⁴ in the outer end of the arm B⁴ permits this movement of the lever B to take place. The spring of the plunger D² is of such strength that in 65 the event of the flotation chamber breaking loose from the anchor, even with the whole length of the mooring cable still attached to

the arm B⁴, it will return the lever B to its original position so as to open the switch C¹ and thus render the mine safe.

It will be seen that by reason of the small movements of the lever B at its point 70 of connection with the flotation chamber, the diaphragm B³ can be made of sufficient thickness and rigidity to withstand high external pressures without danger of leakage.

Although the invention has been described as applied to the safety devices of an electric mine, it is to be understood that it can also be used in conjunction with the safety device or devices of a mechanical mine.

What I do claim and desire to secure by Letters Patent of the United States is:—

1. In a submarine mine comprising a flotation chamber and an anchor which holds the flotation chamber by means of a mooring cable at a predetermined depth beneath the surface of the water, the combination of a safety device which prevents the charge in the flotation chamber from being fired when said mooring cable is not under tension, a member pivoted to said flotation chamber with one part disposed within said chamber for operating said safety device and another part disposed outside said chamber and operated upon by said mooring cable, and a diaphragm at the pivot of said member adapted to prevent the entry of water into said chamber.

2. In a submarine mine comprising a flotation chamber and an anchor which holds the flotation chamber by means of a mooring cable at a predetermined depth beneath the surface of the water, the combination of a safety device adapted to prevent the charge in the flotation chamber from being fired when said mooring cable is not under tension, a member one part of which is disposed within said chamber for operating said safety device and another part is disposed outside said chamber and operated upon by said mooring cable, a two-part ball on said member, a two-part spherical socket on said chamber, said socket receiving said ball, and a diaphragm clamped between the parts of said ball and between the parts of 115 said socket.

3. In a submarine mine comprising a flotation chamber and an anchor which holds the flotation chamber by means of a mooring cable at a predetermined depth beneath the 120 surface of the water, the combination of a plurality of safety devices adapted to prevent the charge in the flotation chamber from being fired when said mooring cable is not under tension, a member pivoted to 125 said flotation chamber with one part disposed within said chamber for operating said safety device and another part disposed outside said chamber and operated upon by said mooring cable, and a dia- 130

phragm at the pivot of said member adapted to prevent the entry of water into said chamber.

4. In a submarine mine comprising a flotation chamber and an anchor which holds the flotation chamber by means of a mooring cable at a predetermined depth beneath the surface of the water, the combination of a plurality of safety devices adapted to prevent the charge in the flotation chamber from being fired when said mooring cable is not under tension, a member one part of which is disposed within said chamber for operating said safety device and another part of which is disposed outside said chamber and operated upon by said mooring cable, a two-part ball on said member, a two-part spherical socket on said chamber, said socket receiving said ball, and a diaphragm clamped between the parts of said ball and between the parts of said socket.

5. In a submarine mine, the combination with the elements claimed in claim 1, of a device adapted to retain the pivoted member in its inoperative position until a predetermined interval of time has elapsed after the mine has been launched.

6. In a submarine mine, the combination with the elements claimed in claim 2, of a device adapted to retain the pivoted member in its inoperative position until a predetermined interval of time has elapsed after the mine has been launched.

7. In a submarine mine, the combination with the elements claimed in claim 1, of a plug of soluble material adapted to normally hold the pivoted member in its inoperative position, a chamber in which said plug is disposed, a plate normally covering an opening in the last-mentioned chamber, and a lanyard connecting said plate to the anchor, whereby when the flotation chamber separates from the anchor said plate will be stripped off to allow water to enter said opening and gain access to said plug.

8. In a submarine mine, the combination with the elements claimed in claim 2, of a plug of soluble material adapted to nor-

mally hold the pivoted member in its inoperative position, a chamber in which said plug is disposed, a plate normally covering an opening in the last-mentioned chamber, and a lanyard connecting said plate to the anchor, whereby when the flotation chamber separates from the anchor said plate will be stripped off to allow water to enter said opening and gain access to said plug.

9. In a submarine mine, the combination with the elements claimed in claim 1, of a plug of soluble material adapted to normally hold the pivoted member in its inoperative position, a chamber in which said plug is disposed, a plate normally covering an opening in the last-mentioned chamber, a lanyard connecting said plate to the anchor, whereby when the flotation chamber separates from the anchor said plate will be stripped off to allow water to enter said opening and gain access to said plug, a member interposed between said pivoted member and said soluble plug, and a shearing pin holding said interposed member in the inoperative position until sheared by the pull of the mooring cable on said pivoted member after said soluble plug has been dissolved.

10. In a submarine mine, the combination with the elements claimed in claim 2, of a plug of soluble material adapted to normally hold the pivoted member in its inoperative position, a chamber in which said plug is disposed, a plate normally covering an opening in the last-mentioned chamber, a lanyard connecting said plate to the anchor, whereby when the flotation chamber separates from the anchor said plate will be stripped off to allow water to enter said opening and gain access to said plug, a member interposed between said pivoted member and said soluble plug, and a shearing pin adapted to hold said interposed member in the inoperative position until sheared by the pull of the mooring cable on said pivoted member after said soluble plug has been dissolved.

HARTLEY BLYTH PRATT.
